UNITED STATES PATENT OFFICE.

JOSEPH CZERNY, OF NEW YORK, N. Y.

CHANDELIER.

1,032,660.

Specification of Letters Patent.

Patented July 16, 1912.

Application filed May 20, 1912. Serial No. 698,372.

To all whom it may concern:

Be it known that I, JOSEPH CZERNY, a citizen of Austria, residing at New York city, county and State of New York, have 5 invented a new and Improved Chandelier, of which the following is a specification.

This invention relates to a chandelier of novel construction and more particularly to improved means for building the chandelier 10 up of a number of separable units and for securing the pendants or glass rods to the chandelier by means of removable carriers.

In the accompanying drawing: Figure 1 is a top view of a chandelier embodying my 15 invention; Fig. 2 a longitudinal section thereof with the pendants or rods partly omitted; Fig. 3 a detail of one of the carriers; Fig. 4 an enlarged section on line 4—4, Fig. 1, and Fig. 5 a detail of part of 20 the chandelier with one of the bars folded.

The chandelier is composed of a plurality of separable units arranged one below the other, so that by multiplying or diminishing the number of such units, the height and 25 appearance of the chandelier and its light sustaining capacity may be varied at pleasure. As shown, each unit is composed of a continuous frame 10, the frames of the various units being alike in form but diminishing 30 in diameter from the top downward. Across each frame extends a spider or open-work member 11, shown to consist of four arms that extend at right angles to each other and which are connected to the frame in suitable manner. To each frame (excepting the top frame) there is pivoted 35 at 12, midway between the arms of its spider 11, a foldable bar 13 adapted to become vertically alined with an arm of the spider 11 next above. Thus with the cruciform spiders shown, each frame is provided with 40 four bars, each bar being centered between a pair of adjoining spider arms. The arms of the spiders (with the exception of those 45 of the bottom frame) are apertured for the passage of the bars 13, pertaining to the frame next below which are adapted to be projected through said apertures at their upper ends and to be removably locked 50 thereto by cotter pins 14 passing through transverse perforations of the bars.

In assembling the parts, the bars of any one unit are swung upward and are passed through the arms of the spider next above 55 to which they are locked by the cotter pins 14. In this way the spider arms of the first,

third, etc., units will become vertically alined with each other, while the arms of the second, fourth, etc., unit which are likewise vertically alined, will bisect the angles 60 of the adjoining units. It will thus be seen that by the construction described, any number of units may be readily coupled to each other, so that a chandelier of any given size and capacity may be built up. In dismembering the device, the bars are withdrawn from the spiders and are folded horizontally against their frame (Fig. 5) so that each unit becomes disconnected and will occupy a very limited space for storage 65 and shipment. It is of course obvious that the bars 13 instead of being swung upward may be swung downward to connect with the unit next below.

To each frame 10 are secured a number 75 of glass rods or pendants 15, those of the lower frame only being fully illustrated. Means are provided for first assembling a row of these rods and for securing the thus 80 assembled rods jointly to the frame in a removable manner. In order to effect this result a plurality of pendants 15 are suspended side by side from a common plate or carrier 16 by means of upper eyes 17 that engage corresponding apertures in the lower 85 portion of the plate. The plate is further provided with a number of key slots 18 which are adapted to be engaged by pins or screws 19 extending from the inner sides of frame 10. By first passing the head of 90 these screws through the enlarged slot-sections and then shifting the plate laterally to cause the screws to enter the contracted slot-sections, the plate may be secured to the frame in a quick and reliable manner. 95 Frame 10 is chamfered along its lower inner edge, while the lower apertured end of plate 16 overhangs said chamfered edge. In this way a clearance is formed between frame and plate which accommodates eyes 17, permits a free play of the glass rods, and conceals the eyes from view. By the use of the plates 16, the glass rods may be quickly strung up in a much simpler manner than when hooked into the chandelier directly. So also the plates charged with 100 the rods may be separately stored and shipped and may be readily attached to chandeliers whenever required.

I claim:

1. A chandelier unit comprising a frame, a spider extending across the same, bars

110

pivoted to the frame, and locking means on the bars.

2. A chandelier comprising a plurality of frames arranged vertically below each other, spiders carried by the frames bars pivoted to the frames, and means on the bars for removably securing them to the spider of an adjoining frame.

3. A chandelier comprising a plurality of frames arranged vertically below each other, spiders carried by the frames and having apertured arms, bars pivoted to the frames intermediate the arms, and adapted to be passed through the apertured arms of an adjoining frame, and means for locking said bars to said last named arms.

4. A chandelier comprising a frame, a carrier, a plurality of pendants suspended

from the carrier, and means for removably securing the carrier to the frame.

5. A chandelier comprising a frame, a number of headed pins extending therefrom, a carrier having key-slots adapted to be engaged by said pins, and a plurality of pendants suspended from the carrier.

6. A chandelier comprising a frame having a chamfered inner edge, a carrier removably secured to said frame and overhanging said edge, a plurality of pendants, and eyes on said pendants which engage the carrier and are accommodated between said carrier and frame.

JOSEPH CZERNY.
